UNITED STATES PATENT OFFICE

JOHN B. GURY, JR., OF ST. LOUIS, MISSOURI, ASSIGNOR TO J. B. GURY MFG. CO., OF ST. LOUIS, MISSOURI, A CORPORATION OF MISSOURI

PUNCHING MACHINE

Application filed January 21, 1931. Serial No. 510,087.

This invention relates to punching machines; and has special reference to punching machines adapted and designed for use in forming rows or lines of punched holes or indentations through or on paper or the like to form the outlines of patterns. Accordingly, an object of the invention is to provide a machine that is easily manipulated and that is operative by electrical energy to drive the punch in one direction, and is equipped with means for breaking the electric circuit in order to permit withdrawal of the punch after each downward movement thereof.

Another object of the invention is to provide an electrical punching machine using alternating current and equipped with secondary winding elements for obtaining induced currents in said elements depending upon position of plunger, so that the plunger will be operated rapidly and satisfactorily by use of a smaller coil winding than would otherwise be possible if the secondary windings were omitted.

Another object of the invention is to produce a punching machine embodying the various improved features of construction capable of operation and cooperation to obtain all of the advantageous results and effects herein disclosed, reference being made to the accompanying drawings, in which—

Fig. 1 is a rear elevation of my improved machine.

Fig. 2 is a side elevation.

Fig. 3 is a vertical cross-sectional view.

Fig. 4 is a detail view showing the improved circuit closer and opener controlled automatically and as an incident to the movement of the machine along the work.

Fig. 5 is a diagrammatic view showing the electrical circuit and switch elements of the device.

Fig. 6 is a side elevation of the tube in which the plunger is mounted and on which the magnet coils are wound.

Fig. 7 is a perspective view of the switch operating member that is controlled by the element shown in Fig. 8 to open the circuit at each downward movement of the punch plunger.

Fig. 8 shows three elevations of an element

that is controlled by the punch plunger to cause the circuit to be opened at each operation of said plunger.

The machine is supported by a base disc 1 arranged to slide along the paper or other material 2 that constitutes the work through which holes are to be punched or other outlines marked by operation of this machine. The disc 1 is formed with a central hole 3 through which the plunger and the switch operating device operate.

A frame 4 is detachably and rigidly secured to the base 1 by a fastener 5. A body 6 is attached to the frame 4 by detachable fasteners 7. A tube 8 has its lower end rigidly secured in a recess in the upper end of the body 6 and projects upwardly therefrom. Electro-magnet coils 9 are wound on the tube 8 between a lower insulation disc 10 and an upper insulation disc 11. The tube 8 has a number of ports 12 for the in and out passage of air below the disc 10, and a number of ports 13 for the same purpose near its upper end. A longitudinal slot 14 is formed in the disc 8 and extends throughout, or almost throughout, the length of the coil windings 9. A purpose of this slot is to break up the eddy currents inside the coil and prevent the flow of the electrical energy circumferentially around the tube 8 within the coil windings.

An iron core 15 having a number of longitudinal grooves 16 to break up eddy currents is mounted for sliding movements within the tube 8. A spring 17 is enclosed within the tube 8 and has its lower end seated against the body 6 and its upper end bearing against the lower end of the iron core 15. The power and energy of this spring 17 is exerted and utilized to raise the iron core 15 to its upper or starting position after each downward movement of said core. As hereinafter disclosed, the core 15 is moved downwardly under the influence of electrical energy and attraction whenever the magnet coils 9 are energized by the closing of the electric circuit. This downward movement of the iron core 15 compresses and increases the energy of the spring 17 so that, when the electric circuit is opened, said spring acts immediately to move the core 15 upwardly to its starting position.

point, which is the position shown in Fig. 28 of the drawings.

A number of metallic discs 18 of graduated sizes encircle the tube 8 above the magnet coils, these discs being of decreasing diameter to the upper one of the series. Said discs 18 are clamped between a supporting ring 19 and a ring 20 that is clamped on the tube 8 against the uppermost disc 18. These discs 18 constitute secondary windings for induced currents and are effective to produce the desired power and speed in a small machine, to prevent heating of the coil, and to cooperate with the coil so that the coil will operate the core and thereby the plunger without making the coil of considerable size, as would otherwise be necessary. This is to say that these discs 18 are essential to obtain proper operation of the machine when the machine is constructed of such a size that it is readily portable and easily manipulated. As shown in Fig. 5, the secondary coil formed by the discs 18 is grounded at one end at 21 and at the opposite end at 22 because these discs 18 are in contact with the tube 8. Each of these discs forms a separate secondary winding having sufficient resistance between each other for the low voltage present.

The upper end of the tube 8 is closed by a plug 23 having one end detachably secured within the upper portion of a clamp 24. The lower end of the clamp 24 is detachably clamped on the upper end of the tube 8 which has its lower end rigid with the body 6. An elastic cushion 25 is secured to the lower end of the plug 23 and constitutes an abutment for a concave piston element 26 rigid with the upper end of a rod 27. The rod 27 projects through the core 15 and said core is slideable along said rod. This construction and cooperative arrangement of the elastic body 25 and the piston 26, which presents a concavity toward said body 25, constitute a shock absorber or cushioning device to prevent damaging percussive action at the end of the upward stroke of the core 15. This cushioning effect is obtained because the concave walls of the piston 26 force the air upwardly within the tube 8 and outwardly through the holes 13; and, as the piston approaches the abutment 25 and the space between the piston and the abutment becomes reduced, the air between said parts constitutes a cushion to soften the percussive effect of the upward movement of the core 15 by the spring 17.

The rod 27 extends downwardly through the core 15 and is attached to the upper end of a plunger 28 which is formed with an enlarged portion 29 operating within a guide 30 formed in the body 6. The lower end of the plunger 28 projects beyond the lower end of the body 6 and constitutes a support and driver for a punching die 31 that is attached to the lower end of the plunger 28. The upper end of the plunger

28 is formed with a head 28^a. When the magnet 9 is energized, the core 15 is moved downwardly along the rod 27 until the lower end of the core strikes against the head 28^a of the plunger 28. Continued downward movement of the core 15 drives the plunger 28 downwardly a sufficient distance to drive the punching die against or through the work.

An electric circuit wire 32 leads to one side of the electro-magnet 9 and the other end of said electric circuit wire has extensions 33 and 34 leading to connection with binding posts 35 and 36, respectively. Both binding posts 35 and 36 are rigidly supported by insulation in connection with a housing 37 and have their respective contact ends 38 and 39 projecting into said housing (Fig. 4).

The other electric circuit wire 40 is connected to a binding post 41 attached to an insulation support 42 which forms a closure for the housing 37. A resilient contact member 43 has one end attached to the binding post 41 and the other end pressing against a switch member 44. The switch member 44 is attached to an insulation piece 45 and has resilient spaced arms 46 and 47 designed and arranged to contact with the contact members 38 and 39, respectively. The insulation piece 45 is attached to an axle 48 mounted for rocking and longitudinal movements in the frame 4. A spring 49 attached to the housing 37 extends downwardly into said housing and engages a bracket 50 attached to the insulation piece 45 and is effective to hold the switch member, comprising the parts 46 and 47, in open position in which said parts 46 and 47 are out of contact with the contact members 38 and 39, but will permit rocking movements of the axle member 48 to move said parts 46 and 47 into contact with the contact members 38 and 39, respectively. Thus, this switch is intended to be closed by means operating the part 48 in opposition to the spring 49, and said spring 49 will operate to open the switch and hold the switch open until the axle member 48 is positively rocked.

The resilient spring contact member 43 cooperates with the spring 49 to hold the axle member 48, and thereby the switch elements supported by said axle member, in their inward position, but will yield to permit outward movement of the axle member 48.

The axle member 48 has its inward extremity 51 pointed and engaging the outer end of the element 52 mounted for sliding movements in a hole in the body 6. The inner end of the element 52 is conical and the point of said element is close to or against the plunger 28 below the enlargement 29. The lower end of the enlargement 29 is formed with a cam or beveled portion 54

which, during the final portion of the descent of the plunger, rubs against the conical end 53 of the element 52 and forces said element 52 outwardly, thereby moving the axle member 48 outwardly in opposition to the springs 43 and 49. To diminish resistance of this outward sliding movement of the element 52, said element is formed with a series of longitudinal grooves or channels 55 (Fig. 8).

A plate 56 is attached to the axle member 48 and has arcuate beveled racks 57 on its opposite ends. A wheel 58 provided with an elastic circumferential portion 59 is rotative on an axle 60 detachably secured to the frame 4. A beveled ratchet or gear wheel 61 is rigid with the wheel 58 and, in the inward position of the axle 48, engages the lower rack 57. However, when the plunger 28 descends, the cam 54 pushes the element 52 outwardly, thereby pushing the axle 48 outwardly and moving the plate 56 outwardly to position in which the rack 57 is out of engagement with the wheel 61. When the plunger 28 is moved upwardly by the spring 17, a distance sufficient to disengage the cam 54 from the cone, the springs 43 and 49 immediately move the axle member 48 inwardly and re-engage the rack 57 with the gear wheel 61, the spring 49 at the same time moving the switch element to position in which the parts 46 and 47 are out of contact with the contact members 38 and 39, thus opening the circuit.

A wire 62 (Fig. 5) leads from the wire 33 to a contact member 63; and a wire 64 leads from the wire 40 to a movable switch member 65, adapted to be moved into contact with the contact member 63 manually and to move out of contact with the contact member 63 automatically.

A handle 66 is rigidly attached to the body 6 of the machine and constitutes means for operating the machine.

In operation, the machine is placed in an upright position upon the work 2, the base 1 being seated on said work. The lower peripheral portion of the elastic wheel portion 59 engages the work 2. The handle 66 is manually engaged and the machine is moved along the work, either forwardly or rearwardly, in a direction at right angles to the axis of the wheel 58, so that said wheel will freely rotate. As the wheel 58 rotates, it rocks the plate 56 and thereby the axle member 48, moving the switch element 46 into contact with the contact member 38, or the switch element 47 into contact with the contact member 39, depending upon the direction of rotation of the wheel 58. As soon as contact is made between the contact members 46 and 38, or between the contact members 47 and 39, the electric circuit is closed, the magnet is immediately energized, and the

core 15 is moved downwardly rapidly and with sufficient force to drive the punch 31 through or into the work 2. Automatically and as an incident to the downward movement of the plunger 28, the cam 54 pushes the element 52 longitudinally in an outward direction, thus moving the axle member 48 longitudinally in an outward direction a sufficient distance to disengage the rack 57 from the gear or ratchet wheel 61. Immediately upon disengagement of the rack 57 from the gear or ratchet wheel 61, the spring 49 acts to disconnect the contact member 46 from the contact member 38, or the contact member 47 from the contact member 39, as the case may be. Thus, the circuit is quickly opened, the magnet is quickly de-energized, and the spring 17 immediately acts to raise the plunger and the magnet core. Immediately upon the raising of the plunger and the movement of the cam 54 away from the conical end 53 of the element 52, the springs 43 and 49 act to move the axle member 48 longitudinally inwardly a distance sufficient to re-engage the rack 57 with the gear or ratchet pinion 61.

In practice, I have found that these operations of the plunger and punch die are rapid and that the machine may be moved rapidly along the work in either direction. This automatic opening and closing of the circuit energizes the magnet with sufficient rapidity and energy to drive the punch die downwardly to produce its intended effect, and the spring 17 operates with approximately equal speed to raise the punch die for the next operation. When it is desired to operate the punch die while the machine remains in a stationary position, such operation can be effected by closing the circuit through the wires 62 and 64 and the switch members 63 and 65.

I am aware that the construction and arrangement of the parts of this machine may be widely varied without departure from the nature and principle of the invention, and I do not restrict myself in any unessential respects. What I claim and desire to secure by Letters Patent is:

1. A punching machine comprising a plunger, a tube in which said plunger is mounted for operation, an electro-magnet supported by said tube for operating said plunger in one direction, a spring enclosed in said tube for moving said plunger in the opposite direction when said magnet is de-energized, automatic mechanism for energizing said magnet as an incident to movement of the punching machine along the work, and means operated by said plunger during movement of said plunger by said magnet to de-energize said magnet.

2. A punching machine comprising a plunger, a tube in which said plunger is mounted for operation, an electro-magnet sup-

- ported by said tube for operating said plunger in one direction, a spring enclosed in said tube for moving said plunger in the opposite direction when said magnet is de-energized, automatic mechanism for energizing said magnet as an incident to movement of the punching machine along the work, means operated by said plunger during movement of said plunger by said magnet to de-energize said magnet, an abutment for limiting extent of movement of said plunger by said spring, and means for preventing percussive action of said plunger against said abutment.

3. A machine of the character described comprising a supporting frame, a plunger carried by said supporting frame, a wheel in connection with said supporting frame arranged to roll along the work to be punched, an actuator for operating said plunger, mechanism operated by said wheel controlling the energizing of said actuator, and devices operated by said plunger for de-energizing said actuator automatically and as an incident to movement of said plunger by said actuator.

4. A machine of the character described comprising a supporting frame, a plunger carried by said supporting frame, a wheel in connection with said supporting frame arranged to roll along the work to be punched, an actuator for operating said plunger, mechanism operated by said wheel controlling the energizing of said actuator, devices operated by said plunger for de-energizing said actuator automatically and as an incident to movement of said plunger by said actuator, a spring for moving said plunger to its starting position, and means preventing percussive action of said plunger when said plunger is moved by said spring.

5. A machine of the character described comprising a normally de-energized electro-magnet, a plunger, means operated by said electro-magnet when said electro-magnet is energized for moving said plunger in one direction, means for energizing said electro-magnet automatically when the machine is moved along the work, and devices operated by said plunger for de-energizing said electro-magnet at each movement of said plunger by said electro-magnet.

6. A machine of the character described comprising a normally de-energized electro-magnet, an instrument, means operated by said electro-magnet when said electro-magnet is energized for moving said instrument in one direction, means for energizing said electro-magnet automatically when the machine is moved along the work, devices operated by said instrument for de-energizing said electro-magnet at each movement of said instrument by said electro-magnet, and means operating with said electro-magnet to prevent eddy currents and heating of said magnet.

7. A punching machine of the character described arranged to move along the work to be punched, a wheel in connection with said machine arranged to engage and roll along the work, a punch device, electro-magnetic mechanism for driving said punch device against the work, devices controlled by said wheel for alternately energizing and de-energizing said mechanism, and mechanism controlled by said punch device for withdrawing said punch device from the work during the time that said electro-magnetic mechanism is de-energized.

8. A punching machine of the character described comprising a wheel arranged to engage and roll along the work to be punched, a punch device, an actuator for driving said punch device against the work, mechanism controlled by said wheel for energizing said actuator, and mechanism controlled by said punch device for de-energizing said actuator.

9. A punching machine of the character described comprising a wheel arranged to engage and roll along the work to be punched, a punch device, an actuator for driving said punch device against the work, mechanism controlled by said wheel for energizing said actuator, mechanism controlled by said punch device for de-energizing said actuator, a spring for moving said punch device from the work, and a device in connection with said punch device for energizing said spring during movement of said punch device by said actuator.

10. A punching machine of the character described comprising a wheel arranged to engage and roll along the work to be punched, a punch device, a normally de-energized electro-magnetic actuator for said punch device, and mechanism controlled by said wheel for intermittently energizing said actuator and causing said actuator to drive said punch device against the work while said wheel is rotating along the work.

11. A punching machine of the character described comprising a wheel arranged to engage and roll along the work to be punched, a punch device, a normally de-energized actuator for said punch device, mechanism controlled by said wheel for energizing said actuator and causing said actuator to drive said punch device against the work while said wheel is rotating along the work, mechanism controlled by said punch device for de-energizing said actuator, and means for withdrawing the punch device from the work when said actuator is de-energized as aforesaid.

12. A punching machine comprising a plunger, a tube in which said plunger is mounted for operation, a normally de-energized actuator for said plunger supported by said tube, mechanism for energizing said actuator automatically and as an incident to the movement of said machine along the work to be punched, a spring enclosed in said tube

for moving said plunger from the work when said actuator is de-energized, and means operated by said plunger for de-energizing said actuator.

- 6 13. A punching machine comprising a plunger, a tube in which said plunger is mounted for operation, a normally de-energized actuator for said plunger supported by said tube, mechanism for energizing said actuator automatically and as an incident to the movement of said machine along the work to be punched, a spring enclosed in said tube for moving said plunger from the work when said actuator is de-energized, means operated by said plunger for de-energizing said actuator, and means for preventing percussive action of said plunger when said plunger is moved by said spring.

14. A portable punching machine movable along the work to be punched and comprising a punch for punching the work, a normally de-energized actuator, automatic means for energizing said actuator during movement of said machine along the work to be punched, 20 automatic means for de-energizing said actuator, a rotary element controlling operation of both of said automatic means, and means other than either of said automatic means for moving said punch from the work after each 25 operation of said punch by said actuator.

15. A portable and manually movable punching machine arranged to be moved manually along the work to be punched, a punch, a normally de-energized actuator for driving said punch against the work, mechanism for energizing said actuator automatically and as an incident to movement of said machine along the work to be punched, and 40 a device operated by said punch for de-energizing said actuator.

16. A portable and manually movable punching machine arranged to be moved manually along the work to be punched, a punch for punching the work, normally de-energized electric mechanism for driving said punch against the work, and mechanism operated automatically and as an incident to movement of the machine along the work for 45 energizing said electric mechanism intermittently.

17. A punching machine comprising a plunger, a punching element in connection with said plunger, a tube in which said plunger is mounted for operation, a support for said tube, a normally de-energized actuator supported by said tube for operating said plunger to drive said punching element against the work while said tube remains stationary in said support, a spring enclosed in said tube for operating said plunger to withdraw the punching element from the work, and mechanism operated automatically and as an incident to movement of the machine 55 along the work for energizing said actuator intermittently.

18. A punching machine comprising a plunger, a tube in which said plunger is mounted for operation, a normally de-energized actuator supported by said tube for operating said plunger in one direction, electric connections for energizing said actuator, mechanism operated automatically and as an incident to movement of the machine along the work for intermittently energizing said actuator by said connections, and manual means for causing said connections to energize said actuator while said machine remains stationary.

19. A punching machine of the character described arranged for manual movement along the work to be punched, a punch device carried by said machine, electric mechanism operated automatically and as an incident to movement of the machine along the work for driving said punch device against the work, and mechanism controlled by said punch device for causing said electric mechanism to operate intermittently.

20. A punching machine of the character described arranged for manual movement along the work to be punched, a punch device carried by said machine, electric mechanism operated automatically and as an incident to movement of the machine along the work for driving said punch device against the work, mechanism controlled by said punch device for causing said electric mechanism to operate intermittently, and means for withdrawing the punch device from the work intermittently with the operation of said punch device by said electric mechanism.

21. A punching machine of the character described arranged to be moved along the work to be operated on, a reciprocating instrument for operating on the work, normally de-energized electro-magnetic mechanism for operating said instrument against the work, mechanism operated automatically and as an incident to movement of the machine along the work for energizing said mechanism intermittently, and a secondary winding device having electric currents induced therein and governed by the position of said instrument and making effective the use of a smaller electro-magnet than could otherwise be used and having power and speed without excessive heat.

22. A punching machine of the character described arranged to be moved manually along the work to be operated on, a reciprocating instrument, normally de-energized electro-magnetic mechanism for driving said instrument device against the work, mechanism for intermittently energizing said magnetic mechanism automatically and as an incident to movement of the machine along the work, and construction preventing eddy currents around the inside of said magnetic mechanism.

23. A punching machine of the character

described arranged to be moved manually along the work to be operated on, a reciprocating instrument, normally de-energized electro-magnetic mechanism for driving said instrument device against the work, mechanism for intermittently energizing said magnetic mechanism automatically and as an incident to movement of the machine along the work, construction preventing eddy currents around the inside of said magnetic mechanism, and devices in connection with said electro-magnetic mechanism for obtaining induced electric current and preventing excessive heating of said magnetic mechanism.
